(57) **CLAIM**

The ornamental design for an enclosure for an electronic circuit with display, as shown and described.

DESCRIPTION

FIG. 1 is a front, top and left side perspective view of an enclosure for electronic circuit with display, showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a back elevation view thereof; and,

FIG. 7 is a bottom plan view thereof.

The broken lines shown in the figure drawings are included for the purpose of illustrating environment and form no part of the claimed design.
